TRIANGULATION APPARATUS FOR DETERMINING THE PATH OF AN AERIAL TARGET

Ernst von Segebaden, Drottningholm, Sweden,
assignor to Areco Aktiebolag, Stockholm,
Sweden, a Swedish joint-stock company

Application June 26, 1944, Serial No. 542,180
In Sweden July 3, 1943

2 Claims. (Cl. 235—61.5)

1

This invention relates to improvements in apparatus for computing the length of one of the catheti of a right triangle in dependence of variations of the angle between said cathetus and the hypotenuse, for use in fire control instruments for antiaircraft guns for ascertaining the path of an aerial target, whereby the cathetus ascertained denotes the horizontal component of the line of sight to the target. Another object of the invention consists in the provision of improved means for automatically ascertaining the length of said horizontal components even at relatively acute angles of elevation of the line of sight to the target.

In the accompanying drawings:

Fig. 1 is an elementary diagram in three dimensions illustrating trigonometrically the main principle involved in the invention, especially when adapted for plotting graphically in a fire control instrument the course of an aerial target to predict the point of impact when firing at said target;

Fig. 2 is a diagrammatic perspective view of certain details of an arrangement for determining and plotting the course of the target;

Fig. 3 is an elevational view, partly in section, of part of the fire control instrument provided with the arrangement as illustrated in Fig. 2;

Figs. 4 and 5 illustrate diagrammatically certain improvements of part of the arrangement as shown in Fig. 2;

Fig. 6 shows an arrangement of apparatus embodying the invention and the general plan on which various components of mechanisms are interconnected or cooperate, respectively.

Fig. 7 is a diagram illustrating the theory of the operation of the device as shown in Fig. 6.

Referring first to Fig. 1 of the drawings, the course of the aerial target F is ascertained by plotting said course on a horizontal image plane A. The line of sight LF from the observing point L to the target F intersects the image plane A at the point P. Assuming that the target flies at a straight-course at constant speed and altitude the point P moves on the image plane in a straight line which represents the course of the target and is parallel with said course. The height of the image plane A above the point L is indicated by h_0 .

The displacement of the point P on the image plane A is determined by variations of the bearing angle s_v and the altitudinal angle h_v of the target. Thus the position of the point P is defined by the length of the co-ordinate p , the distance of the point P from a predetermined point,

e. g. a centre C, and by the angle s_v between the co-ordinate p and a predetermined line of origin CD. The length of the co-ordinate p depends merely on the length of the vertical line CL perpendicular to the image plane A, viz. the height h_0 and the altitudinal angle h_v of the line of sight LF. Hence

$$p = h_0 \cdot \cot h_v$$

10

For the purpose of tracing the course of the target on the image plane A, said plane is turned about its centre proportionally to the angle s_v but in a direction opposite to the azimuthal deflection of the line of sight, and simultaneously the point P represented by the point of a stylus 2 is displaced along a straight radial path into positions given by the formula $p = h_0 \cdot \cot h_v$. Thus on the image plane the line CD is turned whilst the direction of the line CP which contains the stylus 2 is invariable.

The mechanical means for plotting the course of the target F is shown in Figs. 2 and 3. The stylus 2 is mounted on a rod 3 provided with a roller 4. The rod 3 is guided in steady brackets 5 so that it can move rectilinearly only and the roller 4 engages in a spiral groove 6 of a rotary cam disc 7 the centre of rotation of which is positioned in a line with C and L. The cam disc 7 is secured to a rotary shaft 8 which is turned proportionally to the altitudinal angle h_v , measured by a sighting instrument positioned in the observing point L and adjusted to the target F.

It will first be assumed that the curvature of the groove 6 is determined by the formula

$$r = h_0 \cdot \tan \phi$$

in which the angle of rotation of the cam disc 40 7 from an angular position of origin is denoted by ϕ . It is, furthermore, assumed that the cam disc turns through an angle equal to the decrement of the altitudinal angle h_v and that the center lines of the stylus 2 and the roller 4 are 45 collinear, i. e. that $p = r$.

Thus, $p = h_0 \cdot \tan \phi = h_0 \cdot \cot h_v$. But then the pitch of the spiral will be too great, when h_v is small so that the displacement of the rod 3 will, due to frictional resistance, be made difficult or 50 rather impossible. To obviate this, a gear ratio is provided between the sighting instrument at L and the shaft 8 so that a certain variation of the altitudinal angle h_v renders a greater variation of the angle of rotation of the cam disc. 55 If the ratio of the increment of the angle ϕ and

the corresponding decrement of the angle h_v is denoted by k (greater than 1)

$$p = r = h_0 \tan \frac{\phi}{k} = h_0 \tan (90^\circ - h_v)$$

Thus,

$$p = h_0 \cot h_v$$

If $k=4$, for instance, each variation of the altitudinal angle h_v through 1° will correspond to a rotation through 4° of the cam disc 7, so that a complete revolution of the cam disc would theoretically be utilized for adjustment when the altitudinal angle varies from 0° to 90° . Figs. 4 and 5 illustrate the relation between the curves not reduced and those reduced as mentioned above.

The above-mentioned formulae are valid under the presumption that the roller 4 is positioned at the centre of rotation of the cam disc 7 when $h_v=90^\circ$. For constructional reasons this is, however, inconvenient. The inner end of the groove 6 should be located beyond the centre of the disc 7 at a distance r_0 therefrom being the distance between the center lines of the roller 4 and the stylus 2.

Then $p=r-r_0$ and both the above-mentioned formulas will be modified to

$$r = r_0 + h_0 \tan \phi$$

$$r = r_0 + h_0 \tan \phi/k$$

respectively, as shown in Fig. 4, and $p = h_0 \cot h_v$ in both cases.

A disc of glass 11 positioned above the stylus 2 is rotatively journaled about the point C on rollers 10 and coated on its bottom face with a layer of non-drying paint engaged by the stylus 2. Said bottom face of the disc 11 forms the image plate A of the point P. The disc 11 has circumferentially a toothed rim 12 which meshes with a pinion 13 adapted to adjust the disc into angular positions proportional to the azimuthal rotation of the sighting instrument adjusted to the target F. The stylus 2 is so positioned on the rod 3 that its point is positioned at the centre of rotation of the disc 11 when the roller 4 is positioned in the innermost end of the groove 6, viz. when $h_v=90^\circ$. For any value of h_v the point of the stylus 2 will always be positioned by cam disc 7 at a distance from C corresponding to the co-ordinate p of the point P. The disc 11 is turned simultaneously therewith, so that the stylus 2 will on the lower face of the disc 11 plot an image of the path of flight of the target F.

A lattice 14 consisting of straight wires 9 clamped between two annular frames 15 and 16 is positioned above the disc 11. The lower frame 15 is rotatably supported by rollers 17, and the upper toothed frame 16 meshes with a pinion 18 secured to a rotary shaft 19 which by means of a bevel gear 20 is connected to certain mechanisms of the fire control instrument, so that the course of the target is introduced into said mechanism. The shaft 19 and thereby also the lattice 14 are turned by means of a handle 21, so that the wires 9 of the lattice are directed exactly longitudinally of the image of the path of flight as plotted on the disc 11. Thereby the directions of the wires 9 relative to a direction of origin indicate the course of the target F, and said course is by means of the gear 20 introduced to the above-mentioned mechanisms of the fire control instrument.

In the embodiment shown in Fig. 6 the roller 4

guided by the groove 6 (the equation of which will be recited hereinafter) has a pin 22 engaging in a fixed rectilinear guide groove 24 of a bar 25 directed toward the centre of rotation of the disc 7 and further into a rectilinear guide groove 26 of a multiplier arm 27 positioned above the bar 25 and pivoted to a pin 28. A carriage 30 is displaceably mounted on a rod 29 above the multiplier arm 27 and is provided with a transversely directed bar 31. The bar 31 has a rectilinear guide groove 53 which is parallel with the groove 24 and in which there is longitudinally displaceable a rack 32 pivoted to the arm 27 by means of a pin 33 which engages in the guide groove 26 of the arm 27. The rack 32 meshes with a toothed cylinder 34 which meshes with still another rack 35, which may be provided with the stylus 2. Alternatively, the cylinder 34 might be adapted to drive another member of the fire control instrument. A wire 36 parallel to the rack 32 is secured to the carriage 30. An arm 37 is pivotally mounted on a pin 38 and provided with a scale 39 marked in terms that indicate the range of the target, whereby the fulcrum at 38 corresponds to the observing point L. The arm 37 is idly turnable on the pin 38 and engages under the influence of a spring 50 an abutment 51 on a gear wheel 54, so that said arm can be arrested by a stationary abutment 47 on being turned to a position corresponding to an altitudinal angle h_v approaching zero. The arm 27 and thereby also its guide groove 26 are directed perpendicularly to the guide grooves 24 and 53 when the roller 4 is in its innermost position in the guide groove 6, i. e. when $h_v=90^\circ$. The shaft 8 of the cam disc 7 and the pin 38 are interconnected by a control shaft 40 by means of worm gears 41 and 42, so that the ratio of angular movement φ of the cam disc 7 from its position of origin ($h_v=90^\circ$) and the swing of the arm 37 from $h_v=90^\circ$ is $k:1$. The gear 42 drives the toothed wheel 54, to which the pin 38 and the abutment 51 are secured. The shaft 40 is turned by means of a hand wheel 48, and it is by means of a gear 52 connected to the sighting instrument 43, whereby the arm 37 is adjusted into the altitudinal angle indicated by the instrument 43. The carriage 30 is displaced on the rod 29 by means of a hand wheel 44 and a gear 45, so that the wire 36 is adjusted into a position corresponding to the ascertained value of altitude h . This value of altitude corresponds to the distance between the wire 36 and the fulcrum at 38 which is equal to the distance between the fulcrum 28 and the line of center of the groove 53. A translucent plate 55 of glass is mounted above the wire 36, and on said plate the positions of the target can be plotted point by point during the flight, viz. by dotting measured ranges of the target on said plate right above the range scale 39 of the arm 37, the angular position of which is consecutively adjusted in accordance with h_v . Obviously, the distance of each dot from the line 38-B (denoting a horizontal plane) will correspond to the altitude of the target, but, due to unavoidable personal errors in adjustments of the sighting instrument 43 and the telemeter, the dots on the plate 55 will possibly not correspond exactly to the positions of the target. Thus, even though the target is movable in a straight path and at a constant altitude the distance of the dots from the line 38-B might differ slightly.

Fig. 7 illustrates diagrammatically the mode of operation of the device as shown in Fig. 6 for various altitudes. L and L₁ denote the fulcrums

at 38 and 28, respectively, and A denotes the position of the roller 4 when $\phi=0^\circ$, i. e. when the angular position of the cam disc 7 corresponds to $h_v=90^\circ$. Thus, when $h_v=90^\circ$ the points L, L₁ and A are positioned on the same straight line in Fig. 7. The line LB in Fig. 7 corresponds to the line 38—B in Fig. 6. The oblique lines extending from L and L₁ (except the line LF₁) denote angular positions of the arms 37 and 27 respectively.

Assuming that the altitudinal angle h_v decreases, the cam disc 7 will rotate correspondingly from its angular position of origin and displace the roller 4 outwardly from its point of origin A by a distance defined by the formula

$$p=k_1 h_0 \cot h_v = k_1 h_0 \tan \phi/k$$

The curvature of the groove 6 for obtaining such a displacement might be defined by the formula

$$r=r_0+k_1 h_0 \tan \phi/k$$

In this example k_1 is not equal to 1 (as assumed in the embodiment described with reference to Figs. 1 to 5), but it is for constructional reasons less than 1. Of course, this is unimportant with respect to the result obtained, since a reduction of the coefficient k_1 will merely signify a reduction of the size of the groove 6 and not a change of its shape, which is the sole factor defining the course of the target.

By this displacement of the roller 4 the arm 27 is by the pin 22 swung outwardly (to the right in Figure 6). The wire 36 is by means of the hand wheel 44 adjusted into a position right above the average of the actual altitude h plotted on the plate 55. Consequently, also the bar 31 will be adjusted transversely into such a position that the center line of the groove 53 and thereby also that of the rack 32 will be positioned at a distance from the fulcrum at 28 corresponding to the average of altitude h plotted on the plate 55. By this transversal adjustment of the bar 31 the pin 33 will slide in the groove 26 so that the rack 32 is displaced longitudinally in the groove 53 into a position at a distance of $p=k_1 h_0 \cot h_v$ from its position of origin (when $h_v=90^\circ$ and $h=h_0$). Obviously, the multiplier as now described is, however, not necessary for the tracing of the course of the target, since such tracing can be executed irrespective of the actual value of the constant altitude h of the target provided the linear coordinate r of the spiral groove 6 varies in accordance with

$$\tan \frac{\phi}{k}$$

as described heretofore.

Due to rapid increment of r when ϕ/k approaches 90° , i. e. when h_v approaches nil, the curvature of the groove cannot, however, be defined by $\tan \phi/k$ when ϕ exceeds a maximum value corresponding to a minimum value of h_v , for then the frictional resistance will first make the conveying of movements from the arm 27 to the rack 32 difficult and thereafter impossible. Furthermore, the dimensions of the apparatus would in such case be too extensive. Therefore, the curvature of the groove 6 is defined by the formula

$$r=r_0+k_1 h_0 \tan \frac{\phi}{k}$$

between certain limits corresponding to $h_v=90^\circ$ to α is a value elected at will. When h_v is

smaller than α the curvature of the groove is defined by the formula

$$r=r_0+k_1 R \sin \frac{\phi}{k}$$

in which R represents the constant value

$$\frac{h_0}{\sin \alpha}$$

As will be hereinafter proved by mathematical demonstration, this formula can by means of the mechanism shown in Fig. 6 afford the same result, i. e. the same longitudinal movement of the rack 32 as when using the formula

$$r=r_0+k_1 h_0 \tan \phi/k$$

as described hereinbefore.

When the decreasing h_v passes the value α , the arm 37 engages yieldingly the abutment 47. When $h_v=\alpha$, the arm 27 occupies the angular position denoted by the line L₁A α of Figure 7. The swing of the arm 27 continues, however, so that it occupies the position denoted by the line L₁A_{h_v1}, for instance, corresponding to the altitudinal angle h_{v1} . Since

$$\frac{\phi}{k}=90^\circ-h_v$$

the radial displacement A A_{h_v1} of the roller 32 is $k_1 R \cos h_{v1}$ when the roller 4 moves in the portion of the groove 6 that is defined by the formula

$$r=r_0+k_1 R \sin \frac{\phi}{k}$$

By turning the arm 27 the rack 32 is displaced longitudinally and by its own transversal displacement from its transversal position of origin corresponding to the altitude h_0 , said longitudinal displacement of the rack 32 is increased.

When h_v has passed α the wire 36 is, however, not adjusted to correspond to the actual value h_v of the altitude but to a fictitious value of altitude denoted h_1 , viz. by adjusting the wire to the measured range of target $\rho=LF$ on the scale 39 of arm 37 resting against the abutment 47, whereby also the rack 32 is adjusted transversely to said fictitious altitude h_1 . Thus the total longitudinal displacement of the rack 32 will be

$$k_1 \frac{h_1}{h_0} R \cos h_{v1}$$

Referring to Fig. 7, the following relations are evident:

$$h_1=\rho \sin \alpha$$

$$LF=LF_1$$

Thus,

$$\rho=\frac{h}{\sin h_{v1}}$$

Hence

$$h_1=\frac{h \sin \alpha}{\sin h_{v1}}$$

Thus the longitudinal displacement of the rack 32 is

$$k_1 \frac{h \sin \alpha}{h_0 \sin h_{v1}} \frac{h_0}{\sin \alpha} \cos h_{v1} = k_1 h \cot h_{v1}$$

Thus by swinging the arm 27 in accordance with the cosine law the radial displacement of the roller 4 is relatively little, viz.

$$A A h_{v1}=k_1 R \cos h_{v1}$$

so that the longitudinal displacement of the rack 32 caused by turning the arm 27 does not cor-

respond to the actual variation of h_v , but this error is compensated thereby that the transversal displacement of the rack 32 is increased correspondingly, so that the total longitudinal displacement of the rack 32 will always be determined by the formula $p=k_1 h \cdot \cot h_v$.

In the operation of the arrangement as described with reference to Fig. 6 the roller 4 is displaced rectilinearly. This arrangement may, however, be modified so that the pin 22 of the roller 4 is stationarily journaled in the arm 27 at a predetermined distance h_0 from the fulcrum at 28. In such case the guide bar 25 is omitted and the roller 4 moves on a circular path. The rod 32 may, however, also in this case be displaced longitudinally at a velocity determined exactly by the formula $p=h \cdot \cot h_v$ if the curvature of the groove 6 is modified correspondingly, whereby it will approximately be determined by the formula

$$r=r_0 + h_0 \cdot \operatorname{tg} \frac{\phi}{k}$$

or

$$r=r+h_0 \cdot \sin \frac{\phi}{k}$$

respectively.

The altitude h may, if desired, be plotted automatically on the translucent plate 55 if e. g. the arm 37 has a longitudinal guide, in which is movable a slider which is operably connected to a range computing means provided with a stylus, thereby being adjustable longitudinally of the arm 37 in dependence of the range of the target ascertained by a telemeter.

I claim:

1. In a fire control instrument for anti-aircraft guns, a primary element movable in dependence upon varying altitudinal angle of an aerial target, a rotatable member having a spiral guide for displacing said primary element, a turnable multiplying member connected to said primary element and having a rectilinear guide, a secondary element pivotally connected to said multiplying member and movable along said rectilinear guide to be displaced in a predetermined direction in dependence upon angular movements of said multiplying member as well as in dependence of its movements along said rectilinear guide, an image plane for recording altitudes of the target, a range member located at said image plane and having a range scale and being yieldingly operably connected to said rotatable member to turn relative to said rotatable member at the ratio $1/k$, where k is greater than 1, into angular positions corresponding to the altitudinal angle of said target, the curvature of said spiral guide being defined by the formula

$$r=r_0 + h_0 \cdot \tan \frac{\phi}{k}$$

r denoting the linear co-ordinate of said spiral guide, ϕ denoting the angular displacement of said rotatable member from a position of origin, k being a constant greater than 1, r_0 being a constant and h_0 being a constant.

2. In a fire control instrument for anti-aircraft guns, a primary element movable in dependence of varying altitudinal angle of an aerial target, a rotatable member having a spiral guide for displacing said primary element, a turnable multiplying member connected to said primary element and having a rectilinear guide, a secondary element pivotally connected to said multiplying member and movable along said rectilinear guide to be displaced in a predetermined direction in dependence upon angular movements of said multiplying member as well as in dependence upon its movements along said rectilinear guide, an image plane for recording altitudes of the target, a fulcrumed range member located at said image plane and having a range scale and being yieldingly operably connected to said rotatable member to turn relative to said rotatable member at the ratio $1/k$, where k is a constant greater than 1, into angular positions corresponding to the altitudinal angle of said target, a stationary abutment for arresting the swing of said range member when attaining a predetermined minimum value α of the altitudinal angle and when the guide member has been turned correspondingly into the position defined by $\phi=k(90^\circ-\alpha)$, the curvature of said spiral guide being defined by the formula

$$r=r_0 + h_0 \cdot \tan \frac{\phi}{k}$$

when ϕ is greater than α and

$$r=r_0 + \frac{h_0}{\sin \alpha} \cdot \sin \frac{\phi}{k}$$

- 40 when ϕ is less than α , r denoting the linear co-ordinate of said spiral guide, ϕ denoting the angular displacement of said rotatable member from a position of origin, k being a constant greater than 1, r_0 being a constant and h_0 being a constant.
